APPARATUS FOR TREATING DRILLING MUD

Ransome W. Erwin, Fort Worth, Tex., assignor to Salt Water Control, Inc., Fort Worth, Tex., a corporation of Texas

Application June 30, 1952, Serial No. 296,396

7 Claims. (Cl. 183—2.5)

The invention relates to apparatus for treating drilling mud.

In drilling oil wells it is now standard practice to use a circulating liquid commonly called "drilling mud" for the purpose of cooling and lubricating the drill bit, removing cuttings from the hole, lubricating the drill pipe, providing cake or seal lining for an exposed formation hole, and as a controllable hydraulic head or load for prevention of premature flowing of the well. It is with this latter function that this invention is chiefly concerned. The mud is usually made heavier by addition of pulverized barites or barium sulfates. As the drilled hole goes deeper greater earth rock pressures are encountered and thus greater oil or gas pressures, if the driller is fortunate enough to find them. It is standard practice to carry surplus weight in the drilling mud as a safety factor in anticipation of abnormal gas pressures. As the hole deepens the specific gravity of the mud is progressively increased to provide this safety factor. An ideal system would be one where the mud is just heavy enough to suppress fluid flows from formation being drilled, with only enough additional weight to offset the lightening effect of gases released from the drilled up formation in the well bore itself. If the mud is much heavier than the formation pressures encountered then in many rotten or very porous formations the serious hazard of "lost circulation" or mud loss to the formation arises. Thus, the driller cannot just add a large surplus of weighting materials to his mud in order to be sure to prevent formation flows while drilling. He must operate between two serious limitations. If his mud is too light, hydrocarbons or salt water may flow from the formation and blow the mud column from the hole. If the mud is too heavy it may break down a formation and flow into it instead of circulating back to the surface. If this happens with the mud being lost faster than it can be replaced, then the mud column in the well will be shortened, and possibly sealed off zones at a higher level may break through and start flowing. Either of these two conditions may cause "blowouts" due to inability to control the flow, resulting in loss of well, equipment, lives and even whole oil reservoirs.

But even when operating between the above limits the process may get out of hand if, for instance, a thick gas distillate bearing zone is being penetrated. As the zone is drilled, all the hydrocarbons contained in the drilled up portion are picked up by the circulating mud. These may be quite condensed as liquids under the pressures at the drill bit, but as the mud rises to the top of the well with steadily diminishing pressure on it, these liquefied gases turn into gases, expand and lighten the mud by gasifying or "gas cutting" it. If this gas is not removed and the mud recirculated it picks up still more gas, making the mud even lighter, necessitating addition of weighting materials if the well has not already started flowing due to loss of weight control on it. Thus, the thorough removal of entrained gases and lighter liquid

2

hydrocarbons from the drilling mud is quite important in drilling oil or gas wells.

Most prior drilling rigs attempt removal of lighter components by flowing the mud through long troughs or ditches and by agitation of the mud with jet nozzle guns in mud tanks. Such prior processes have succeeded in removing only a portion of the gas, and rely on carrying extra weight in the mud to offset gas that cannot be removed. There have been several mud degassing devices built and used, but most have been discarded for one reason or another. Today the large majority of drilling rigs rely solely on ditches and mud gun jet nozzles in pits, which are far short of what is wanted. In the average mud system it costs about \$3000.00 in labor and weighting materials to add one pound per gallon of weight to the mud when its density is over ten or twelve pounds to the gallon. Many rigs carry at least two pounds per gallon extra weight on the mud purely for a margin of safety against possible gas cutting. Obviously, a reliable and operable mud degasser that would remove all gases and lighter hydrocarbon liquids from all the mud as it comes from the well, thus breaking the accumulating cycle, would lessen the need for this five or six thousand dollars worth of extra weighting material. Also, carrying two pounds per gallon less weight would greatly lessen the likelihood of formation break down with resultant mud losses.

Thus, the principal object of this invention is to continuously and conveniently remove all or nearly all entrained or dissolved gases and light liquid hydrocarbons from all the drilling mud in an oil or gas well drilling operation as it comes from the well and prior to its circulation back into the well.

Another object is to provide an efficient apparatus for removing this gas with complete wash flushing out facilities to obviate formation of hard mud cake and sediment in said apparatus.

Another object is to provide a mud degasser with no valves or moving parts in the flow path of the mud. This is important because of the abrasive nature of the mud and its tendency to coat up and clog up all parts it contacts.

Another object is to provide an unrestricted flow path through the degasser with no small ports or openings that could be plugged by coarse material in the mud.

Another object of this invention is to provide a small compact apparatus that is designed to provide the same surface area exposure that only a much larger vessel or container would offer in other degasser designs; one that fits easily astride any mud trough on a drilling rig without additional floor space.

Another object is, by use of high vacuum and great area exposure of mud, to remove gases without the violent agitation or centrifuging characteristic of certain other mud degassers. It has been found that while centrifugal whirling of the mud separates gas from it, such action also throws out suspended weighting material, which tends to defeat its purpose.

It has been observed that aeration of gas cut mud in some cases facilitates removal of the gas. The present invention provides for admixture and agitation of mud with air just as the mud enters the vacuumed degasser, if conditions warrant it. However, it should be noted that a great excess of air should be added to avoid chances of making an explosive mixture of air and gases.

Another object is to provide vacuumed cascading of the mud without gas and mud interference or counter-flow, as is set forth in the specific description of the invention.

Another object is to provide ample shut-off devices to positively assure no accidental sucking of mud into the gas withdrawal vacuum pump.

Another object is to provide a mud degasser so arranged that in case of its shut-down for any reason, accidental or otherwise, the circulating mud will automatically bypass the degasser and assume the path it would have followed if no mud degasser were provided.

Another object is to provide a qualitative gas detector that will record and notify the driller when hydrocarbon gas is being removed from mud. By recording this on a chart with a clocking arrangement synchronized with a drilling depth log chart, it is possible to determine approximately the depth of the bit when the gas is produced.

Another object is to meter the removed gases giving important meaning to such data since in this process all of the mud is being completely and continuously degassed. This step too, can be synchronized and correlated with a well depth log which is a conventional apparatus now in use on many drilling rigs.

Gas detectors and alarms are now available and in use on mud streams in some drilling rigs, but unless substantially all the gas is removed from the mud prior to its circulation back into the well a qualitative gas indication would have little or no meaning. However, if all gas is removed in the mud's cycle, then the gas detector provided on this mud degrasser or in the mud stream ahead of it would hold much meaning and logging information. My object is to provide substantially gas-free mud re-entering the drilling well to give meaning to gas detecting efforts.

Where it is convenient to use electric power to drive the motor on the gas evacuating pump it is an object of this invention to provide still another gas indicating and metering device. I have found that when no gases are being produced with the mud, the vacuum pump does little work, thus using a minimum of electric power in the motor. However, as soon as any gas is produced the pump starts doing work, immediately putting a proportionate power demand on the motor. Thus, a power meter on the circuit of the motor, both visible and recording, would provide another gas logging method. This log would indicate all gases being handled, both air and hydrocarbons. If produced water vapour should confuse this power measurement logging method then it may be removed by placing a dessicant dryer in the suction line to the vacuum pump. In many cases this would be constant and its removal unnecessary.

Another object of the invention is to so locate the mud degasser that, if desired, mud containing all the bit cuttings will pass through the degasser before undue exposure to atmosphere. The novel design of the mud degasser so exposes the oil and gas formation cuttings to an intense vacuum that many of the hydrocarbons inherent in their pore spaces will be evacuated by the vacuum pump. With the use of an instrument now on the market, it is possible to qualitatively record and indicate whether the hydrocarbons are light like methane, or are heavier gasoline vapours. If they prove to be gasoline vapours then this fact would indicate oil or gas distillate formation cuttings, as contrasted to dry gas.

I believe that I am the first to provide a practicable method for insuring thorough and complete exposure of all the well cuttings to a vacuum for removing hydrocarbon. This is accomplished by extensive surface exposures and cascading of all the mud. This novel design also makes ample provision against undue dropping out of sediments and cuttings by avoiding large volume settling spaces, due to its compact and constant travel design. It provides maximum surface exposure with minimum volume space. If some of the cuttings do settle out they may be completely flushed out periodically by a novel washing arrangement. Water, which is often added as liquid make up to the system, may be used for flushing out these cuttings, or pressured degassed mud from a conditioner pump may be used when no water is needed in the mud system.

The invention will be more readily understood by ref-

erence to the accompanying drawings and to the following detailed description in which the invention is illustratively embodied.

In the drawings:

5 Fig. 1 is a perspective view somewhat diagrammatic in character of my combined mud degasser and hydrocarbon logging device;

10 Fig. 2 is a diagrammatic view showing the mud degasser and hydrocarbon logging device with connections to a well undergoing a rotary drilling operation, some of the details of the degasser and hydrocarbon logging device which are shown in Fig. 1 being omitted for simplicity and to more clearly illustrate the system as a whole; and

15 Fig. 3 is a vertical section through the degasser taken substantially on line 3-3 of Fig. 1.

20 Referring first more particularly to Figs. 1 and 3, gas cut mud from source 1 enters a mud trough 2 through outlet 3 prior to entry into a mud degasser tank 62. The source is usually the shale shaker or discharge from a 25 choke manifold, or it may be the drilling well head itself, ahead of the shale shaker. The mud degasser tank 62 may be a welded pressure vessel approximately three feet in diameter and about ten feet long. It is mounted horizontally astride the mud trough 2, somewhere between the mud line choke manifold from the drilling well and the usual mud conditioning pits, one of which is shown at 69 in Fig. 2. The gas cut mud is picked up by vacuum from the sand trap or sump 4 through suction pipe inlet 5. This pipe is usually a light gauge 8" diameter 30 conduit that may be adjusted for suction depth by means of dresser union 7. The gas cut mud is pulled into the top portion of the degasser at 8 through a cut-a-way overflow pipe 9 open at the top, the end of which is capped at 10. Periodically the pipe 9 should be thoroughly flushed out by high pressure wash water from perforated wash pipe 42 within the pipe 9.

35 The gas cut mud overflows from the open topped pipe 9, radially, then passes down over a pair of downwardly and outwardly inclined cascade plates 11. These plates spread the mud out into a thin sheet of considerable area, thus, subjecting the mud to eight or ten inches of vacuum by means of which the entrained and dissolved gases are removed. Also, any highly volatile liquid hydrocarbons such as distillates will be vaporized and flashed. The mud 40 is further exposed by passing from plates 11 to a pair of downwardly and inwardly inclined cascade plates 12 (Fig. 3) back towards the center of the degasser vessel. Then the mud falls onto a pair of inclined roof top cascade plates 13 to split into two streams, going to the 45 lower part of the degasser shell.

50 At this point all or most of the gas should be now removed from the mud. The degassed mud now enters a U-type liquid seal discharge 15 at outlet 14. This device also comprises a light gauge 8" diameter conduit

55 pipe whose suction inlet is in the head of the vessel as near the bottom of the shell as is possible to construct. The degassed mud passes through the discharge pipe 15 and into a reducing jet housing 17 at the point 16. The jet housing 17 may be removed for cleaning or inspection by screwing it out of the coupling 39. The degassed mud is pulled from the vacuumed degassing vessel 60 by means of a jet nozzle 38. This is usually a 3/4" orifice mud conditioning gun nozzle which may be reached for cleaning or changing by unscrewing pipe 17 from the coupling 39.

65 The source of jet power for this nozzle is preferably pressured mud from the conditioner circulating pump. The pressured mud preferably comes from a pump 70 (Fig. 2) to enter the jet system at 39 through valve 37. The mud is expanded through jet nozzle 38, pulling out degassed mud and re-entering the mud trough at 18. From here the degassed mud passes, conventionally, to a cuttings removing shale shaker 67 (Fig. 2) and then to one or more mud tanks or pits 69 to be picked up by one or more mud pumps 70 for re-

75 turn to the drilling well.

As the gases (air and hydrocarbons) are removed from the large exposed mud surfaces, it is vitally important to remove them with a minimum of countercurrent contact with a curtain of cascading mud. This is efficiently accomplished by special pairs of vent pipes 65. Only one pair is shown, but the degasser preferably has several pairs of these vent pipes, which also act as tie members between the cascade plates. These vent pipes receive gas through openings 19, 20 and 21 (Fig. 3). Opening 19 at the top takes gas removed from the first pair of cascade plates 11. Opening 20 receives gas removed from the roof top cascade plates 13. Opening 21 receives gas removed from mud as it flows from the bottom of shell 62 to outlet 14. Gas removed from the second pair of cascade plates 12 goes directly to a main gas outlet or pick up pipe 23. All other gas picked up through afore-described vent pipes 65 goes out opening 22 to main outlet pipe 23.

All the removed gases pass through main pickup pipe 23 and through a float actuated valve 24 having a float 59. The float 59 will rise with the mud level in the degasser in case of flooding and shut off valve 24 before mud reaches the gas discharge pipe 23, thus precluding the possibility of pulling mud into the gas discharge outlet. The removed gas passes up discharge riser 25 through pipe union 58. This pipe union 58 permits facile removal of gas pickup pipe 23 and valve 24 for cleaning, repair or inspection. The gas goes up through an inverted U-riser loop 26, and then passes down into a conventional float actuated liquid trap 28 (float not shown) at point 27. Riser loop 26 is high enough to make the lifting of heavy mud to its peak impossible, should the float valve 24 fail. This is another safety precaution to avoid pulling mud into the vacuum pump 32. Should any foam or liquid condensates form or carry over with the gasses, it will be caught in trap 28. The internal construction of the trap is not shown, as it is a well known and widely used appliance. When the liquid builds up in the trap, a float closes the outlet, thus preventing pulling liquids into vacuum pump 32. Gases pass from float trap 28 through outlet 29, then through pressure reducing regulator 30 to vacuum pump 32 at entrance 31. This conventional vacuum pump 32, which may be driven by any power desired or convenient, discharges the gases at 33 to pass through gas detector 34. The gas detector is another widely used instrument that indicates the slightest trace of hydrocarbon gases. A direct reading meter 61 may be placed where the driller can see it by connecting wires 60. Also, a recording chart (not shown) may be incorporated in this setup. The gas passes on from gas detector 34 through a conventional gas meter 63 to atmosphere at 35. Gas meter 63 can be a recording type, thereby facilitating the use of this setup for gas logging and correlation.

Another feature of the invention is the controlled aeration of the mud, if needed. Many muds give up their hydrocarbon gases more readily when air is mixed with them, and they are then subjected to vacuum for removal of air and hydrocarbons. This may be readily accomplished in this system by means of the wash pipe 42 in overflow pipe 9. Instead of using water in wash pipe 42, as would normally be the case, air inlet valve 64 may be opened (with water valve 41 closed) thus thoroughly aerating and agitating mud in pipe 9 just prior to its overflow into the degasser.

The importance of being able to thoroughly and easily wash every part of the degasser is very great. The tendency of mud to coat and cake up on the surfaces is well known and has always been a serious problem in mud handling equipment. If allowed to go too long, some of it sets and becomes almost as hard as portland cement. It, therefore, is highly important that this cake accumulation, as well as sand and cuttings sediments, be periodically flushed out of mud handling devices. It is for this

reason that so much attention is given washing jets and wash pipes in this mud degasser design.

Wash water from a pump (not shown) providing both great volume and pressure, comes to a wash pipe manifold at 40 (Fig. 1). If there is a water source of ample volume and pressure, all wash valves 49, 41, 43, 45 and 47 may be opened at once to wash down and flush out the degasser when it is not in operation. If there is a limited volume in the water supply, then each wash pipe valve should be operated singly. Valve 41 controls the supply of wash water to perforated wash pipe 42 within the open topped inlet pipe 9, which washes out inlet pipe 9. Valve 43 controls wash water to a pair of perforated wash pipes 44, which wash down the first pair of cascade plates 11. Valve 45 controls wash water to perforated wash pipes 46, which wash down the second or lower pair of cascade plates 12. Valve 47 controls wash water to a double row perforated wash pipe 48, which washes down each side of roof top cascade plates 13. Valve 49 controls wash water to wash pipe 50, which contains jet nozzles 51 for flushing sediment from the bottom of degasser shell to outlet 14. Discharge pipe 15 contains a drain valve 53 to be opened when the degasser 62 is being washed down.

For inspection and manual cleaning, if needed, manway 57 at the front end of shell 62 is provided to permit access to all cascade baffles. The manway also permits access to the float 59 and valve 24 on the gas discharge pipe assembly.

Vacuum gauges 54, 55 and 56 provide a picture of functions in the system. If the tank tends to flood and valve 24 closes, then vacuum gauge 54 will read less than gauge 55. If regulator 30 fails to function, then gauges 55 and 56 will probably read the same, whereas normally regulator 30 will provide less vacuum on gauge 55 than on gauge 56. If the float valve is closed in the drip pot 28 the vacuum in gauges 54 and 55 will both go to zero, while 56 will show an abnormally high vacuum.

Reference will now be made more particularly to Fig. 2 of the drawings which diagrammatically illustrates the mud cycle and gas handling only but does not attempt to show baffling or washing feature details of the degasser itself, these having been already described in connection with Figs. 1 and 3.

Gas free high pressure mud from pump 70 is forced through pipe 71 to drill pipe 73 at drill pipe entrance 72. The mud goes down inside the drill pipe and comes out through the drill bit 74. The drill bit is assumed to be operating in a freshly drilled, exposed gas formation 75. This mud flows out of the bit, lubricating and cooling it, picks up drilled formation cuttings and passes out through an annular space between the hole 75 or casing liner 76 and drill pipe 73. Since it is in a gas zone, the mud picks up entrained gases from cuttings and gas that may escape before the porous wall is plastered with the mud. The mud with the entrained gases rises up through annular space to well head 77 and passes out through the discharge pipe at 1. The mud enters the sand trap or reception well 4 and is sucked into mud degasser 62 by pipe 8.

In the degasser 62, by cascading the mud through a vacuum, most or all of the gaseous hydrocarbons are removed and withdrawn by vacuum pump 32 through outlet pipe 23. The gas passes successively through float actuated valve 24, outlet pipe 25, inverted U-riser 26, automatic shut-off liquid trap 28, vacuum reducing regulator 30, vacuum pump 32, qualitative electronic gas detector 34, volume gas meter 63 and thence to atmosphere at 35. Recording and visible power meter 66 on vacuum pump 32 measures electric power consumed by the pump motor, giving a direct indication of the work performed by vacuum pump. Recording and visible electronic hydrocarbon meter 61 on gas detector 34 gives a qualitative record of the hydrocarbon gases exhausted from the mud degasser.

The degassed mud is rapidly passed on out of the degasser 62 with subjection to no "dead spaces" or volume retention that would permit settling of cuttings or weighting materials. The degassed mud then goes through outlet 14 to liquid seal legs 15, through reduced jet housing pipe 17 and back into mud trough 2 at 18. The mud is pulled from the degasser by the jetting action of high pressure degassed mud. The high pressure mud comes from high pressure line 71 at 36, through valve 37 and out through jet nozzle 38. It rejoins the low pressure degassed mud, which passes on to the cuttings removing shale shaker 67. The mud leaves the shale shaker, goes down mud ditch 2 to discharge 68 where it dumps into mud pit or tank 69. From here the mud is picked up by pump 70 for recycling back into the drilling well.

Should the degasser 62 fail to pick up all the mud entering sand trap 4, this mud would rise up and flow over the dam 100 which, as shown, is higher than the intake 5 of pipe 8, and thence on down mud trough 2 directly to shale shaker 67, and on to the mud tank 69. This automatically acts to avoid interruption of the mud cycle, which is of vital importance in the drilling operations.

Manhole 57 at the end of tank 62 is provided to give complete inspection and cleaning access to cascade baffles and float actuated gas outlet valve 24.

If, for any reason, accidental or otherwise, the suction flow through the degasser should be stopped, the sand trap 4 would fill with mud which would well up and travel down the mud trough 2 to shale shaker 67 and on to outlet 68 and thence to mud pits 69. Thus, the mud degasser would automatically be by-passed, avoiding any confusion or loss of mud. This novel suction and discharge arrangement makes this possible.

The invention has been described in detail for the purpose of illustration, but it will be obvious that numerous modifications and variations may be resorted to without departing from the spirit of the invention.

I claim:

1. An apparatus for continuously degassing mud, comprising a closed mud degassing vacuum tank having an inlet conduit for gas-laden mud, an outlet conduit for degasified mud leading from the tank, and means for causing the flow of mud into, through and out of said mud degassing tank, said means comprising a jet nozzle for discharging mud into the outlet conduit beyond the degassing tank, and means for supplying degassed mud under pressure to said jet nozzle.

2. In a drilling mud degassing system, a closed mud degassing vacuum tank having an inlet pipe for gas laden mud, means, including a receptacle, for receiving degassed mud from the degassing tank, means, including an outlet pipe from the degassing tank, for discharging degassed mud from the degassing tank into the receptacle, a mud return pipe leading from the receptacle to the degassing tank outlet pipe having a jet nozzle for discharging mud into said outlet pipe beyond the degassing tank, and pump means in said return pipe between said receptacle and said jet nozzle for applying pressure to the returned mud, said jet nozzle serving to draw mud into, through and out of said degassing tank.

3. In a mud degassing system, a mud degassing vacuum tank having an inlet for gas-laden mud and an outlet for degassed mud, a passageway for degassed mud leading from the degasser, liquid seal means interposed between the passageway and the mud degasser outlet, a mud re-circulating means comprising a pipe connected at one end to the passageway and communicating at its other end with a jet at the exit from the liquid seal means at a point beyond the mud degasser outlet, and a circulating pump in said return pipe, whereby returned mud

serves to draw mud to be treated into, through and out of the degasser vacuum tank.

4. In a drilling mud degassing system, a mud degassing vacuum tank having an inlet pipe for gas-laden mud, a receptacle for degassed mud from the degassing tank, liquid seal means interposed between the degassing tank and the receptacle, a mud return pipe leading from the receptacle to the liquid seal, a jet nozzle in said return pipe at the exit from said seal means and beyond the degassing tank, and a pump in said return pipe for supplying pressure to the circulating mud, said jet serving to draw mud into, through and out of said degassing tank.

5. In a drilling mud degassing system, a receptacle for gas-laden mud from the drilling well, a mud degassing vacuum tank having an inlet pipe communicating with said receptacle, a second receptacle for degassed mud from the degassing tank, a liquid seal interposed between the degassing tank and the second receptacle, a mud return pipe leading from the second receptacle to the liquid seal, a jet nozzle in said pipe at the exit from said seal and beyond the degassing tank, and a pump in said return pipe for supplying pressure to the circulating mud, said jet serving to draw mud into, through and out of said vacuum tank.

6. In a mud degassing system, a horizontally extending mud conduit, having a receptacle at each end, a closed vacuum mud degasser tank extending above the mud conduit and receptacles, said degasser tank having an inlet pipe for mud to be degassed extending into the first receptacle and an outlet conduit for discharging degassed mud leading into the second receptacle, the first receptacle having overflow means leading to said conduit at a level above the degasser inlet, whereby untreated mud would rise in the first receptacle and overflow through the conduit in case of stoppage through the degasser.

7. In a system of handling drilling mud including a drilling well having a mud inlet leading thereto and an outlet therefrom for gas-laden drilling mud, a receptacle for receiving gas-laden mud from said well outlet, a second mud receptacle spaced down stream from the first receptacle, a closed mud degasser vacuum tank above the receptacles having an inlet pipe extending into the first receptacle and an outlet conduit for degassed mud leading to the second receptacle, means for returning mud under pressure from the second receptacle to the drilling well, and an overflow mud conduit means above the entrance to the inlet pipe and leading from the first mud receptacle to the second for bypassing drilling mud directly to the second receptacle without passing through the degasser, in case of stoppage of said mud degasser.
